UNITED STATES PATENT OFFICE.

HENRY J. NUTRIZIO, OF NEW YORK, N. Y.

DESIGN FOR A DISPLAY-SHELF SUPPORT.

54,671.

Specification for Design.

Patented Mar. 9, 1920.

Application filed August 8, 1919. Serial No. 316,275. Term of patent 14 years.

To all whom it may concern:

Be it known that I, HENRY J. NUTRIZIO, a citizen of the United States, and a resident of the city of New York, borough of Manhattan, in the county and State of New York, have invented a new, original, and ornamental Design for a Display-Shelf Support, of which the following is a specifica-

tion, reference being had to the accompanying drawing, forming part thereof.

The figure is a perspective view of a display shelf support, showing my new design.

I claim:

The ornamental design for a display shelf support, as shown.

HENRY J. NUTRIZIO.
